UNITED STATES PATENT OFFICE.

JOHN ROWBOTHAM, OF PHILADELPHIA, PENNSYLVANIA.

ROTARY WATER-METER.

SPECIFICATION forming part of Letters Patent No. 325,361, dated September 1, 1885.

Application filed December 1, 1884. (No model.)

To all whom it may concern:

Be it known that I, JOHN ROWBOTHAM, a citizen of the United States, and a resident of Philadelphia, Pennsylvania, have invented 5 certain Improvements in Water-Meters, of which the following is a specification.

My invention consists of certain improvements, fully described and claimed herein-after, in that class of water-meters in which 10 water admitted to a casing is measured by vanes caused by the pressure of water to revolve in the said casing, my improvements being directed to the accurate and economical manufacture of meters of this class, and to 15 mechanism combined with the meter for causing the same to operate the shaft which actuates the indicator.

In the accompanying drawings, Figure 1, Sheet 1, is a vertical section of my improved 20 water-meter; Fig. 2, a transverse section on the line 1 2, Fig. 1; Fig. 3, a diagram showing the character of the indicator-gearing; Fig. 4, Sheet 2, perspective views of the two parts of the drum detached from each other; and 25 Fig. 5, perspective views showing the sliding vanes of the drum.

The outer casing, A, of the machine consists of a cylinder, *a*, closed at one end, *b*, the other end, *d*, being composed of a cover screwed 30 or otherwise detachably secured to the cylindrical portion *a* of the casing, which has an inlet branch, *e*, and outlet branch, *f*.

The construction of the drum B and sliding vanes D and E will be particularly described 35 herein-after. One journal, *h*, of this drum has its bearing in a projection, *m*, on the portion *b* of the casing, the bearing for the other journal, *i*, being in a projection, *n*, in the cover *d*.

The bearing *t*, made in the interior of the 40 casing for the ends of the vanes, is made in the arc of a circle, of which the axis of the drum is the center, and extends from *x* to *y*.

The drum revolves in contact, but not severe frictional contact, with a portion of a 45 partition or filling-piece, G, the portion of the latter which coincides with the drum extending from *w* to *v*, and the remaining portions, *k k*, of the said partition being clear of the drum, as shown in Fig. 1.

The action of the meter under pressure of 50 water or other fluid entering the branch *e* will be readily understood without explanation. It

will also be understood how the quantity of water discharged at the outlet *f* can be determined by first ascertaining the capacity of 55 the space bounded by the drum and bearing *t* and the vanes D and E, when the latter are in the position shown in Fig. 1, and noting the speed at which the drum revolves.

The drum B consists of two castings, (shown 60 in perspective in Fig. 4,) an annular rim, *j*, on one casting fitting into a corresponding annular recess in the adjoining casting, so that the accurate coincidence may always be assured, screws or bolts *q*, passing through lugs *p p*, 65 serving to secure the two parts of the drum together.

Slots *S S'*, arranged at right angles to each other, would separate each section of the drum into four parts but for the central hub, *u*, and 70 in these slots the vanes D and E fit snugly but so as to slide freely, each vane having a slot, *s*, so that the vanes may cross each other, the slots in the vanes being of such width.

The above-mentioned journal *h* is cast on 75 the central hub of one part of the drum, and the journal *i* on the central hub of the other part.

The drum, constructed in the peculiar manner described, is an important feature of my 80 invention, as it can be put together with that regard to accurate fitting which must be observed in the making of water-meters.

The drum is fitted for use in the following manner: First, the inner face of each part of 85 the drum is faced in a lathe and the recess is turned on one part to receive the annular rib on the part, after which the two parts are bolted together, the drum is chucked in a lathe, its periphery and ends turned, as also 90 are the journals and other parts which have to fit accurately to the casing, after which the slots *S S'* of the drum are preferably milled out, the two parts of the drum separated, and the vanes, which have been properly planed, 95 introduced into the slots, and the two parts of the drum again bolted together. After the segmental bearing-surfaces *t* and *c* of the casing, the inner faces of the end *b*, and cover *d* have been properly turned, and the bearings 100 for the journal bored, the drum is introduced into the casing and the cover *d* secured to the same.

It will be seen that the work to be done on

the meter is that of simple turning, planing, boring, and milling by tools of ordinary construction.

The vanes, which are of uniform thickness throughout and can therefore be easily planed, have extended bearing-surfaces, and this and other advantages, as regards construction, will be readily recognized by expert mechanics.

On the cover *d* is cast a box, *H*, provided with a plate, *I*, detachably secured to the box, which must be water-tight. This box contains the gearing through the medium of which the drum of the meter is caused to turn a shaft, *W*, the latter being connected with the mechanism which operates the pointers of an indicator, which may be substantially the same as that of an ordinary gas-meter. The gearing contained in the box may be varied; but I prefer that shown in the drawings, which consists of a worm-wheel, *J*, into which gears the threaded end portion of the journal *i*, the shaft *K*, having a pinion or forming part of a pinion, *M*, which gears into a wheel, *N*, on the said shaft *W*, the latter passing through a stuffing-box, *g*, on the plate *I*. Owing to this manner of connecting the drum with its gearing by forming on the end of the journal a worm or screw which is no larger than the bearing for the journal, the indicator and drum can be at any time readily disconnected for examination, removal, or repairs by simply unscrewing the cover of the casing and withdrawing the journal from its bearing.

The box may be filled with oil or equivalent liquid, in order to maintain the journals of the shafts in a constantly-lubricated condition, although water from the meter will find its way into the box, or provision may be made for permitting the water to enter the same, and this will suffice to lubricate the journals of the shafts.

The avoidance of tortuous passages in water-meters is an important desideratum, for the attainment of which I arrange the inlet and outlet passages in such relation to the casing, drum, and vanes that a volume of water will take the slightly-curved but comparatively-direct course, indicated by the arrows,

from the inlet to the outlet; for, although the water has free access to the space above the dotted line 2, Fig. 1, the water lodged therein is in a quiescent state. The space, therefore, cannot interfere with the free flow of water in the direction pointed out. The inlet and outlet passages are in line with each other, as indicated by dotted lines 3 3, which are away from the axis of the drum, and at right angles to a line, 4 4, drawn through the axis and bisecting the bearing-surfaces *c* and *t*.

I have shown the portion *k* of the partition *G* as provided with recesses; but I do not here claim them, as they form part of the subject of a separate application filed by me March 13, 1885, Serial No. 158,706.

Although I have heretofore referred to a water-meter, the invention may be used as a motor, in which case one of the journals of the drum will project through its bearing, and will be furnished with a driving wheel or pulley.

I claim as my invention—

1. The herein-described drum for a water-meter, said drum being slotted and made in two parts detachably secured to each other, and having vanes adapted to slide in said slots, substantially as set forth.

2. The herein-described drum for a water-meter, said drum being made in two parts detachably secured to each other, and each part having four sections united by a central hub, and vanes adapted to the slots between the sections, substantially as described.

3. The combination of the meter-casing having a removable cover with a rotary drum provided with journals and bearings for the journals of the drum and indicator-gearing, one of the said journals having a threaded end no larger than its bearing to engage with said gearing, as set forth.

In testimony whereof I have signed my name to this specification in the presence of two subscribing witnesses.

JOHN ROWBOTHAM.
